UNITED STATES PATENT OFFICE.

ALBERT A. SMITH, OF FALL RIVER, MASSACHUSETTS, ASSIGNOR OF ONE-HALF TO
GEORGE W. HOAR, OF FALL RIVER, MASSACHUSETTS.

DISTRIBUTING-JOINT FOR PLASTIC COATINGS.

1,033,283.

Specification of Letters Patent.

Patented July 23, 1912.

Application filed March 6, 1912. Serial No. 681,950.

To all whom it may concern:

Be it known that I, ALBERT A. SMITH, a citizen of the United States, residing at Fall River, in the county of Bristol and State of Massachusetts, have invented certain new and useful Improvements in Distributing-Joints for Plastic Coatings, of which the following is a specification.

The hereinafter described invention is an improvement over the subject matter of Patent No. 986,514 granted to me March 14th, 1911, and it relates to distributing joints for plastic, especially cement, coatings, being especially applicable for roofing and it will generally be described in such use hereinafter.

It is a well known fact that concrete or cement roofs and other plastic coatings when exposed to the elements or to varying degrees of temperature expand and contract in accordance therewith, thus cracking and buckling in case no means of compensating for this action be provided. My said Patent No. 986,514 is aimed to cure this ill, but it will only take up movement in two of the four directions, that is to say from the left and right.

The object of the present invention is to provide a joint to be laid loosely on the roof boards or foundation in a certain order or arrangement before the plastic coating is applied and by such arrangement and the individual form of each distributing joint dividing the plastic coating into sections and distributing the strain and stress equally in all directions throughout the whole coating, thus preventing the above mentioned objectionable cracking and buckling entirely, and to this end my invention consists in the construction, arrangement and combination of parts hereinafter described and claimed and illustrated in the drawings forming a part of this application.

In the accompanying drawings, Figure 1 represents a plurality of distributing joints forming the subject matter of my invention arranged in accordance therewith on a roof or other foundation, the nails C being omitted and the coating not applied; Fig. 2,

a longitudinal vertical section on the line 50 2-2 of Fig. 1, the nails C being shown together with the plastic coating; and Fig. 3, an enlarged detail perspective view of one of my distributing joints or sections. Fig. 4 is a section through the overlapped joint. 55

Referring now in detail to the drawings, A designates the roof boards or other foundation and B the plastic coating of cement or other analogous material adapted to be applied to said roof or foundation and held 60 thereto by hardening around the heads of nails C driven in said boards or other foundation and left with their heads extending slightly above the surface thereof for this purpose. Of course any other common and suitable means of securing the coating on the roof boards or other foundation may be substituted for the above, this not forming part of my invention.

The distributing joint designated generally as 1 may be stamped out or otherwise formed integrally of any flexible metal, copper, however, being preferred. Each joint or section is composed of a central stem and two integral prongs 2 extending at acute 70 angles therefrom. Said prongs and stem each consist of one central V-shaped fold and two parallel side flanges 3 extending at acute angles from the lower edges of said central fold. It is obvious that the side 80 flanges 3 cannot be formed at the point where the prongs 2 join the central stem, the whole joint or section being integral, hence the adjacent ends 4 of the prongs 2 are beveled on the angle of the flanges 3 and 85 take the place thereof; see Fig. 3. From the above it will be seen that the flanges 3 and the sides of the central folds of the stem and prongs 2 form valleys or gutters and that the valleys or gutters of the two 90 prongs 2 lead into and have communication with the respective valleys or gutters of the central stem, thus providing for the drain of any water that may work down between the sides of the central folds and the 95 plastic material, in case the joints be used in a roof or other inclined coating.

In applying my invention to a roof, I

apply a plurality of said distributing joints or sections 1, arranging them in rows, having the joints or sections in one row 5 arranged with the prongs 2 pointing downward, those of the adjacent row 6 with the prongs 2 pointing upward and those of the next adjacent row 7 with the prongs 2 pointing downward &c., the ends of the downwardly pointing prongs 2 of rows 5 and 7 10 overlapping the ends of the upwardly pointing prongs 2 of row 5 and the lower ends of the central stems of one joint overlapping the upper ends of the next lower joint in all the rows, thus making a water-tight arrangement and provision for drainage. The nails C are first driven into the roof boards or other foundation, leaving their heads slightly above the surface thereof, the sections are loosely arranged or laid as above 15 explained on the roof boards, there being no connection between them and the roof. The plastic coating material is then laid on over the roof boards and the rows of distributing joints or sections 1, leaving the tops of the 20 central folds exposed and being careful not to disturb their arrangement above described. It will be seen that when the plastic material hardens it will have tongues fitting snugly in the valleys or gutters respectively, above described, thus providing a 25 strong lock between said plastic material and said expandible distributing joints.

From the above described arrangement of the expandible distributing joints or sections 30 1 it is obvious that the plastic coating will be divided into a plurality of sections bounded on each side by said expandible distributing joints, hence any expansion or contraction due to heat or cold respectively will be 35 absorbed evenly by said distributing joints 1 throughout the entire coating, thus the stress and strain will be distributed evenly. It is also to be noted that any water working its way between the plastic material and the 40 central folds will be received and carried off from one joint to another until the roof gutter or edge of the roof be reached by said valleys hereinbefore described, thus the roof 45 will be perfectly waterproof.

50 It is perfectly obvious that this invention is not restricted to use in roofing, but is capable of use and may be used in connection with flooring, walls, &c., where it is desired to apply a coating of plastic material which 55 will be subject to changes in temperature and will therefore expand and contract in accordance therewith.

Having thus described my invention, what I claim as new and desire to secure by Letters Patent is:

1. An expandible distributing joint for a plastic coating comprising a central stem and two prongs projecting at acute angles therefrom, said stem and prongs having cen-

tral folds and integral side flanges parallel thereto, said flanges, with the respective sides of said folds, forming valleys and the valleys of said prongs leading into the respective valleys of said stem. 65

2. An expandible distributing joint for a plastic coating comprising a central stem and two prongs projecting therefrom, said stem and prongs having central folds, and means for locking said joint in engagement with the plastic material of said coating. 70

75 3. An expandible distributing joint for a plastic coating comprising a central stem and two prongs projecting therefrom, said stem and prongs having V-shape central folds, and means of positive engagement between said joint and the material of said plastic coating. 80

85 4. A foundation and a plastic coating applied thereto, in combination with a plurality of expandible distributing joints arranged in rows loosely over said foundation before said coating is applied, said joints each having two prongs projecting at acute angles from a central stem and means for positive engagement with the material of said coating, the joints of alternate rows having their prongs project upward and the joints of the intervening rows having their prongs project downward, the ends of the 90 downwardly projecting prongs overlapping the ends of the upwardly projecting prongs and the lower ends of the central stems overlapping in all rows the upper ends of the 95 central stems of the next lower joints, substantially as set forth. 100

105 5. A foundation and a plastic coating applied thereto, in combination with a plurality of expandible joints arranged in rows over said foundation before said coating is applied, said joints comprising a central stem, prongs projecting at acute angles therefrom and means for positively engaging the material of said plastic coating, the joints of alternate rows having their prongs project upward and the joints of the intervening rows having their prongs project downward, the ends of the downwardly projecting prongs overlapping the ends of the 110 upwardly projecting prongs and the lower ends of the central stems overlapping the upper ends of the central stem of the next lower joints, said positive engaging means providing a draining means, substantially as set forth. 115

120 6. A foundation and a plastic coating applied thereto, in combination with a plurality of expandible joints arranged in rows over said foundation before said coating is applied, said joints comprising a central stem, prongs projecting therefrom at acute 125 angles, and means for positively engaging the material of said plastic coating, the joints of alternate rows having their prongs

project upward and the joints of the intervening rows having their prongs project downward, the ends of the downwardly projecting prongs overlapping the ends of the 5 upwardly projecting prongs and the ends of said central stems overlapping in all rows.

In testimony whereof, I have signed my

name to this specification in the presence of two subscribing witnesses.

ALBERT A. SMITH.
